[57] CLAIM

The ornamental design for a docking station for extending the functions of a laptop computer, as shown and described.

DESCRIPTION

FIG. 1 is a front elevational view of a docking station for extending the functions of a laptop computer showing my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a perspective view thereof; and,

FIG. 8 is a reduced perspective view thereof with a personal computer connected and shown in broken lines for illustrative purposes only and forming no part of the claimed design.
